ANTIRATTLE DOVETAIL FOR DOORS

Raymond G. Moore, Bridgeport, Conn., assignor
to The Bassick Company, Bridgeport, Conn., a
corporation of Connecticut

Application April 20, 1933, Serial No. 667,012

12 Claims. (Cl. 16—85)

The present invention relates to improvements in self-adjusting anti-rattle dovetails, particularly for automobile doors, an object being to provide a device of this character of simple, economical, and compact construction which will effectually prevent the rattle usually resulting from the vibration and weaving of the doors, retaining the same against vertical movement, while at the same time compensating for lateral movement and wear. Another object is to provide a dovetail device which will permit closing and opening of the door with comparatively little effort, will require little or no lubrication, and will be free from squeaks. A further object is to provide a dovetail in which the contacting surfaces may be of very hard smooth material, as hardened steel, to the end that the device will be long-wearing and will not require lubrication of the contacting surfaces. It is particularly proposed to provide a device in which a socket member is provided with pivotally mounted resiliently supported dovetail members adapted to have a wedge member engaged between them, the respective dovetail members being supported against vertical movement. Another object is to provide a device in which the vertical pressure will be taken along a given line of the door pillar in any position of engagement of the door. Another object is to provide a device in which the dovetail members will be in the form of hollow shell-like blocks, and in which the spring means will be self-contained within the members, thus providing a structure which may be easily assembled and which at the same time is very compact.

Another object is to provide a device in which the lateral movement of the dovetail members is relatively small while the effective engaging relation with the door carried member is relatively great corresponding to the full lateral closing movement in relation to the dovetail. A further object is to provide a device which while having a full effective movement will be relatively narrow, and may therefore be used upon narrow door pillars, requiring a substantially smaller recess in the pillar than has heretofore been the case.

Another object is to provide a device which while holding the door against vertical vibrations will exert an outward force on the same in such manner that the latch of the door is held firmly against the striker plate, and upon release of the latch will press the door open.

With the above and other objects in view, an embodiment of the invention is shown in the accompanying drawing, and this embodiment will

be hereinafter more fully described with reference thereto, and the invention will be finally pointed out in the claims.

In the drawing:

Fig. 1 is a perspective view, partially broken away, of a door and pillar post slightly out of engagement, and provided with a dovetail device according to the illustrated exemplary embodiment of the invention.

Fig. 2 is a side elevation of the dovetail.

Fig. 3 is a front elevation.

Fig. 4 is a horizontal sectional view, taken along the line 4—4 of Fig. 2.

Fig. 5 is a side elevation of the wedge member employed.

Fig. 6 is a top plan view thereof.

Fig. 7 is a side elevation of the dovetail with a portion of the cover plate and a portion of one of the block members broken away, the broken away portion of the cover plate being indicated by dot-and-dash lines.

Fig. 8 is a rear elevation, partially broken away.

Fig. 9 is a perspective view of one of the block members.

Fig. 10 is a plan view thereof.

Fig. 11 is a side elevation of the same.

Fig. 12 is a side elevation of the dovetail, and showing the engaging relation of the wedge member in the closed position of the door, the wedge member being shown in section.

Similar reference characters indicate corresponding parts throughout the several figures of the drawing.

Referring to the drawing, the device, according to the illustrated exemplary embodiment of the invention, comprises a socket member adapted to be secured to the pillar post 10 within a suitable cut-out recess, and a wedge member adapted to be secured to the edge of the door 11 in relation to enter the socket member upon closing the door, as clearly indicated in Fig. 1.

The casing of the socket member comprises an outer part consisting of a face plate 12 preferably formed of sheet metal, having a flange 13 at its forward edge bent at a slightly obtuse angle, 100 and a lip 14 bent forwardly from the flange 13. A rearwardly converging opening 15 is provided in the face plate and extends across the flange 13 to the lip 14. Screw holes 16 are provided in the plate and flange for attaching to the door frame.

The inner or box part of the casing is preferably formed of sheet metal, and comprises a base portion 17 flush with the lip 14, a wall extending at right angles to the base portion having upper 110

and lower curved portions 18—18 providing semi-circular sockets for pivotally supporting the swinging block members, as will hereinafter more fully appear, rearwardly inclined rear wall portions 19—19 extending tangentially from the socket portions 18—18, and upper and lower attaching ear portions 20—20 extending at right angles to the wall and secured to the under side of the face plate, as by spot welding, holes 21—21 10 being provided in the ears to clear the countersunk screw holes 16.

Each of the block members 22—22 is in the form of a hollow shell, the side wall of which comprises a cylindrical bearing portion 23 adapted 15 to fit in the respective socket portion 18 of the casing, a rear wall portion 24 extending tangentially from the portion 23, an arcuate wedge engaging portion 25, and an inwardly extending forward wall portion 26 disposed between the forward end of the arcuate portion 25 and the cylindrical portion 23.

A post 27 having a flanged end 28 is secured within the block, as by riveting at 29, in coaxial relation to the axis of rotation of the block, a coil 25 spring 30 being mounted on the post and having one end 31 bearing against the forward inner surface of the block and the other end 32 bearing against a lug 33 struck up from the portion 17 of the casing. The spring thus exerts pressure on the block member to normally swing it outwardly, the outward swing being limited by abutment of the wall 24 with the lug 33. In order to facilitate assembly an opening 34 is provided in the wall 24 which is slightly higher than 35 the lug 33, and which permits the block to be slid into the casing simply by passing the opening 34 over the lug 33 and snapping the block into place in the socket 18, the spring end 31 which lies against the wall 24 in the detached 40 relation of the block being pressed by the lug into its compressed relation, as clearly indicated in Figs. 2 and 7 and in which relation it exerts pressure on the block to retain it in relation with the socket portion 18.

45 The wedge member comprises an attaching base 35 having screw holes 36 and a rigid projecting wedge shaped projection 37 having flat converging contact surfaces 38—38.

The arcs of the wedge engaging surfaces 25 of 50 the blocks are eccentric to the pivotal axes of the blocks, and in such relation to the angle of the wedge surfaces 38—38 that the lines of contact upon entering of the wedge, as shown in Fig. 2, are in substantially a vertical plane with the pivotal axes of the blocks. As the wedge enters 55 and presses the blocks inwardly the lines of contact increase their distance apart in correspondence with the taper of the wedge member while as the same time remaining in substantially the vertical plane of the pivotal axis, as indicated in Fig. 12.

The operation is as follows:—

When the door is in open position the blocks are projected forwardly, as indicated in Figs. 65 1 and 2. As the door is closed the wedge member engages between the blocks contacting therewith before the door is completely closed, and as indicated in dot-and-dash lines in Fig. 2. The complete closing of the door causes the blocks 70 to be swung inwardly against the pressure of the springs 30 which hold the blocks snugly against the wedge member. The lines of contact being substantially in the vertical plane of the pivotal axes at all times rigidly supports the door against 75 vertical movement, the inclination of the wedge

surfaces being such that vertical pressure will not displace the blocks and cause vibration. The swing of the tangential surfaces 24 of the block members in relation to the tangential casing surfaces 19 is relatively small in relation to the effective movement permitted the door in relation to the dovetail so that a very narrow casing may be employed. The relatively large extent of the cylindrical bearing surfaces 18 and 23 provides a widely distributed very substantial support against the vertical pressure applied against the block members, so that any unusual stresses will be adequately provided for without danger of breakage or distortion. 80 85

The door is provided with the usual latch, not shown, which engages behind a striker on the door pillar, and the present device is such that it permits the door to close sufficiently to allow the latch to operate, and thereupon exerts an outward pressure on the door to force the latch bolt tightly against the striker. Upon release of the latch the device exerts an opening pressure on the door. 90 95

Should the wedge member be out of alignment with the socket, due to sagging of the door or inaccurate mounting of the wedge member, the independent movement of the respective blocks will permit them to adjust themselves to the wedge surfaces and perform their cooperative retaining function. 100 105

While I have shown the socket member on the door pillar and the wedge member on the door it will be obvious that this arrangement may be reversed, if desired.

I have illustrated and described a preferred 110 and satisfactory embodiment of the invention, but it will be obvious that changes may be made therein, within the spirit and scope thereof, as defined in the appended claims.

Having thus described my invention what I 115 claim and desire to secure by Letters Patent is:—

1. In an anti-rattle device for doors, a socket member, and a wedge member adapted to be engaged therewith, said socket member comprising a casing, opposed pivotally mounted elements 120 within said casing having fixed pivotal axes and adapted to be swung through engagement of the wedge member therewith, resilient means disposed forwardly of the rear surfaces of said elements and acting between said elements and the 125 casing to oppose said swinging movement, and means adapted to prevent vertical movement of the contact surfaces of said elements within said casing.

2. In an anti-rattle device for doors, a socket member, and a wedge member adapted to be engaged therewith, said socket member comprising a casing, opposed pivotally mounted elements 130 within said casing having fixed pivotal axes and adapted to be swung through engagement of the wedge member therewith, resilient means disposed forwardly of the rear surfaces of said elements and acting between said elements and the casing to oppose said swinging movement, there 135 being a clear space between the rear surfaces of said elements and the rear surfaces of said casing, and means adapted to prevent vertical movement of the contact surfaces of said elements within said casing.

3. In an anti-rattle device for doors, a socket 145 member, and a wedge member adapted to be engaged therewith, said socket member comprising a casing, opposed pivotally mounted elements within said casing having fixed pivotal axes and adapted to be swung through engagement of the 150

140 145 150

- wedge member therewith, said elements each having a pocket at one side adjacent a surface of said casing, spring means disposed within said pockets and acting between said elements and the casing to oppose said swinging movement, and means adapted to prevent vertical movement of the contact surfaces of said elements within said casing.
4. In an anti-rattle device for doors, a socket member, and a wedge member adapted to be engaged therewith, said socket member comprising a casing, opposed pivotally mounted elements within said casing having fixed pivotal axes and adapted to be swung through engagement of the wedge member therewith, said elements each having a pocket at one side adjacent a surface of said casing, a coil spring within each of said pockets having its coil coaxial with the pivotal axis of the respective element and having a pair of spring ends, one of which contacts said casing and the other of which contacts a side of said pocket to oppose said swinging movement, and means adapted to prevent vertical movement of the contact surfaces of said elements within said casing.
5. In an anti-rattle device for doors, a socket member, and a wedge member adapted to be engaged therewith, said socket member comprising a casing, opposed pivotally mounted elements within said casing having fixed pivotal axes and adapted to be swung through engagement of the wedge member therewith, said elements each having a pocket at one side adjacent a surface of said casing, a post within each of said pockets coaxial with the pivotal axis of the respective element, a coil spring within each of said pockets having its coil disposed about said respective post and having a pair of spring ends, one of which contacts said casing and the other of which contacts a side of said pocket to oppose said swinging movement, and means adapted to prevent vertical movement of the contact surfaces of said elements within said casing.
6. In an anti-rattle device for doors, a socket member, and a wedge member adapted to be engaged therewith, said socket member comprising a casing, opposed pivotally mounted elements within said casing having fixed pivotal axes and adapted to be swung through engagement of the wedge member therewith, said elements each having a pocket at one side adjacent a surface of said casing, said casing surface having a lug disposed within each of said pockets, spring means disposed within said pockets and acting between said elements and said lugs to oppose said swinging movement, and means adapted to prevent vertical movement of the contact surfaces of said elements within said casing.
7. In an anti-rattle device for doors, a socket member, and a wedge member adapted to be engaged therewith, said socket member comprising a casing, opposed pivotally mounted elements within said casing having fixed pivotal axes and adapted to be swung through engagement of the wedge member therewith, said elements each having a pocket at one side adjacent a surface of said casing, said casing surface having a lug disposed within each of said pockets, spring means disposed within said pockets and acting between said elements and said lugs to oppose said swinging movement, a side wall of each of said pockets having an opening through which said respective lugs pass into said pockets as said elements are assembled into said casing, and means adapted to prevent vertical movement of the contact surfaces of said elements within said casing.
8. In an anti-rattle device for doors, a socket member, and a wedge member adapted to be engaged therewith, said socket member comprising a casing, opposed pivotally mounted elements within said casing having fixed pivotal axes and adapted to be swung through engagement of the wedge member therewith, said elements each comprising a hollow metal shell providing a pocket adjacent a surface of said casing, spring means disposed within said pockets and acting between said elements and the casing to oppose said swinging movement, and means adapted to prevent vertical movement of the contact surfaces of said elements within said casing.
9. In an anti-rattle device for doors, a socket member, and a wedge member adapted to be engaged therewith, said socket member comprising a casing having upper and lower concave walls, each forming an arc of a circle, and a rear wall having upper and lower rearwardly inclined portions extending in tangential relation to said respective upper and lower walls, opposed pivotally mounted elements within said casing having bearing portions rotatably engaging said end walls and rearward portions in tangential relation to said bearing portions and adapted to abut said respective upper and lower rear wall portions of said casing, the pivotal axes of said elements being fixed and said elements adapted to be swung through engagement of the wedge member therewith, resilient means opposed to said swinging movement, and means adapted to prevent vertical movement of the contact surfaces of said elements within said casing.
10. In an anti-rattle device for doors, a socket member, and a tapered wedge member adapted to be engaged therewith, said socket member comprising a casing, opposed pivotally mounted elements within said casing adapted to be swung through engagement of the wedge member therewith, resilient means disposed forwardly of the rear surfaces of said elements and acting between said elements and the casing to oppose said swinging movement, the contact surfaces of said elements being non-yielding in a direction perpendicular to the direction of relative engaging movement of said members and presenting a wedge receiving recess between them and adapted as said wedge member is moved inwardly to widen at a given point vertically in substantial correspondence to the increasing width of the wedge member.
11. In an anti-rattle device for doors, a socket member, and a wedge member adapted to be engaged therewith, said socket member comprising a casing having perpendicularly aligned bearing portions at its upper and lower ends, opposed pivotally mounted elements within said casing having pivotal movement in relation to said bearing portions and adapted to be swung through engagement of the wedge member therewith, spring means acting between said elements and the casing to oppose said swinging movement and also acting to retain said elements in relation with said bearing portions, said elements adapted to be removed from said casing by overcoming the retaining pressure of said spring means.
12. In an anti-rattle device for doors, a socket member, and a wedge member adapted to be engaged therewith, said socket member comprising a casing having perpendicularly aligned bearing portions at its upper and lower ends, opposed

5	pivottally mounted elements within said casing having pivotal movement in relation to said bearing portions and adapted to be swung through engagement of the wedge member therewith, spring means carried by said elements acting between said elements and the casing to oppose	80
